UNITED STATES PATENT OFFICE.

DONALD M. SMITH, OF JEANNETTE, PENNSYLVANIA, ASSIGNOR TO MCKEE GLASS COMPANY, OF JEANNETTE, PENNSYLVANIA, A CORPORATION.

DESIGN FOR A TUMBLER OR SIMILAR ARTICLE.

Application filed October 17, 1925. Serial No. 15,159. Term of patent 14 years.

To all whom it may concern:

Be it known that I, DONALD M. SMITH, a citizen of the United States, residing at Jeannette, in the county of Westmoreland and State of Pennsylvania, have invented a new, original, and ornamental Design for Tumbler or Similar Article, of which the following is a specification forming part thereof.

The figure is a side elevation of a tumbler showing my new design.

I claim:

The ornamental design for a tumbler or similar article, as shown.

DONALD M. SMITH.
